UNITED STATES PATENT OFFICE.

ARTHUR LOPEZ, OF NEW YORK, N. Y., ASSIGNOR TO THE HAMMOND TYPEWRITER CO.,
A CORPORATION OF NEW YORK.

TYPE-SHIFTING ATTACHMENT FOR TYPE-WRITING MACHINES.

1,131,640.

Specification of Letters Patent.

Patented Mar. 9, 1915.

Application filed July 30, 1913. Serial No. 781,957.

To all whom it may concern:

Be it known that I, ARTHUR LOPEZ, a citizen of the United States of America, residing in New York, in the borough of Manhattan, county and State of New York, have invented certain new and useful Improvements in Type-Shifting Attachments for Type-Writing Machines, of which the following is a specification.

- 10 This invention relates to an improved type-shifting attachment for typewriting machines, and more especially for the Hammond typewriting machine, by which the shuttle and anvil carrying the same can be
15 lifted from the normal position for printing lower-case letters to an intermediate position and an upper position for printing respectively, upper-case letters and figures, punctuation marks and other characters.
20 For this purpose, one capital shift-key and one figure shift-key are arranged at one side, and a second capital shift-key is arranged at the other side of the keyboard of the machine, whereby the shifting from lower-case
25 to upper-case type is conveniently accomplished, the key-levers for the shift-keys being all connected with one transverse rock-shaft from which the motion is transmitted to the anvil-shaft and anvil of the machine.
30 In the accompanying drawings, Figure 1 represents a plan-view of a typewriting machine of the Hammond type, showing the connection of the shift-keys for upper-case letters and figures with an intermediate anvil-operating rock-shaft, Fig. 2 is a detail side-elevation, partly in section, on line 2, 2, Fig. 1, and Figs. 3 and 4 are details of the locking mechanism for the shift-keys.

Similar letters of reference indicate corresponding parts throughout the several figures of the drawings.

Referring to the drawings, *a* represents the usual type-keys, *a*¹ a shift-key for upper-case letters, and *a*² the shift-key for figures, punctuation marks, etc. A shift-key for capital letters is arranged at each side of the keyboard, one *a*¹ in proximity to the figure shift-key and the other capital shift-key *a*³ at the opposite side of the keyboard, so that the operator can use either capital shift-key as found most convenient in printing. The shift-keys are applied to key-levers *b*¹, *b*², *b*³ respectively, which are applied to the opposite ends of a rock-shaft *s* that extends across the machine, said rock-shaft being

supported in suitable bearings *s*¹ on the bed-plate *s*² of the machine. Alongside of the levers of the shift-keys are fixed on the rock-shaft *s*, the hubs of dogs *d*, *d*¹, which extend under the key-levers, dog *d* extending beneath levers *b*¹, *b*², and dog *d*¹ extending beneath the lever *b*³. A spring *h* beneath the lever *b*¹ and a spring *h*¹ beneath the lever *b*³ lifts the capital shift-keys from depressed to raised position.

From a point on the rock-shaft *s*, midway between its ends, extends a lever *c* on the rear-end of which the anvil-shaft *c*¹ is supported, so that by depressing either one of the shift-keys, the shaft and anvil, together with the shuttles on the same, are raised for the required extent so as to bring either one of the type-lines of letters of the upper case, figures or punctuation marks up to a level with the printing point of the machine. The key-lever *b*¹ of the left-hand capital shift-key is provided with an adjustable stop *g* vertically below the same, by which the extent of lifting of the anvil and the shuttle is accurately controlled. A similar stop *g*¹ limits downward movement of the figure shift-key. The lever *b*³ of the capital shift-key *a*³ at the right-hand side of the keyboard is guided in a slot in the cross guide-bar *f* for the key-levers, the lower edge of the slot acting in the nature of a stop for the same.

The key-lever *b*¹ is provided with a locking-device, which consists of upwardly-extending arm *e* pivoted to the lever and provided with a knob at its upper end. The arm has a hook *e*¹ that enters into a slot *e*² of the key-lever guide-bar *f* of the machine and retains the key-levers depressed. The key-lever *b*² is provided with a like locking mechanism comprising an arm *i* having a hook *i*¹ at a higher elevation than hook *e*¹ and adapted to enter a slot in the bar *f* for retaining the lever *b*² depressed to a lower point than the bar *b*¹. When it is desired to print upper-case letters exclusively, the capital shift-key lever is locked in position and the anvil is thus held in position so that the type in the intermediate row of the shuttle is printed. When figures, etc. are to be continuously printed, the figure shift-key is depressed and locked. Both locking mechanisms are arranged at the left-hand side of the machine, while the shift-key mechanism on the right-hand side is not pro-

vided with a locking device, as the same is employed as an auxiliary convenience in printing, so as to quickly permit the printing of an upper-case letter.

5 By arranging all the key-levers of the shift-keys in connection with one rock-shaft, one anvil-operating arm only is required and the separate connection of the shift-keys dispensed with. All the shifting operations
10 are accomplished by the connection of the key-levers of the shift-keys with the transverse rock-shaft ^s referred to, so that the shifting from lower case to upper case and to figures and punctuation marks is facilitated and accomplished by a simplified and effective mechanism.

I claim:

1. A shift-key attachment for typewriting machines, comprising a capital shift-key 20 and a figure shift-key at one side of the keyboard, and an auxiliary capital shift-key at the other side of the keyboard, key-levers for said shift-keys having circular hubs, a transverse rock-shaft to which the key-levers are loosely applied, two dogs fixed on 25 said rock-shaft and extending one below one of said capital key-levers and the figure-lever, and the other under the other capital key-lever, each dog comprising a circular
30 collar and a radially projecting lug extending exposed in the path of the key-lever radially beyond the hub of the same, independent lifting-springs one under each of the capital key-levers, and a rearwardly-extending arm fixed on said rock-shaft and engaging the lower end of the anvil-shaft of the machine.

2. In a typewriting machine, the combination, with a vertically-shiftable anvil 40 provided with one or more type-shuttles, and its shaft, of two capital shift-keys arranged one at each side of the keyboard, a figure shift-key arranged at one side of the keyboard adjacent to the capital shift-key 45 on that side, key-levers for said shift-keys, said key-levers having circular hubs, independent lifting springs for the capital key-levers, a rock-shaft to which all said key-levers are loosely applied, fixed dogs on said 50 rock-shaft, one of said dogs extending beneath one of said capital key-levers and the other dog extending beneath the other capital key-lever and the figure key-lever, each dog comprising a circular collar and a radially 55 projecting lug extending exposed in the path of the key-lever radially beyond the hub of the latter, a rearwardly-extending center-arm fixed on the rock-shaft and engaging the lower end of the anvil-shaft, and 60 means for locking the capital and figure shift-keys at one side of the keyboard in lowered position.

3. A shift-key attachment for typewriting machines, comprising a capital shift-key 65 and a figure shift-key at one side of the key-

board, and an auxiliary capital shift-key at the other side of the keyboard, key-levers for said shift-keys having circular hubs, a transverse rock-shaft to which the key-levers are loosely applied, two dogs fixed on said 70 rock-shaft and extending one below one of said capital key-levers and the figure-lever, and the other under the other capital key-lever, each dog comprising a circular collar and a radially projecting lug extending exposed in the path of the key-lever radially beyond the hub of the latter, independent lifting-springs one under each of the capital key-levers, a rearwardly-extending arm fixed on said rock-shaft and engaging the 75 lower end of the anvil-shaft of the machine, and means for limiting downward movement of one of said capital key-levers.

4. A shift-key attachment for typewriting machines, comprising a capital shift-key and a figure shift-key at one side of the keyboard, and an auxiliary capital shift-key at the other side of the keyboard, key-levers for said shift-keys having circular hubs, a transverse rock-shaft to which the 80 key-levers are loosely applied, two dogs fixed on said rock-shaft and extending one below one of said capital key-levers and the figure-lever, and the other under the other capital key-lever, each dog comprising a circular collar and a radially projecting lug extending exposed in the path of the key-lever radially beyond the hub of the latter, independent lifting-springs one under each of the capital key-levers, a rearwardly-extending arm fixed on said rock-shaft and engaging the lower end of the anvil-shaft of the machine, and means for limiting downward movement of one of said capital key-levers.

5. A shift-key attachment for typewriting machines, comprising a capital shift-key and a figure shift-key at one side of the keyboard, and an auxiliary capital shift-key at the other side of the keyboard, key-levers for said shift-keys having circular hubs, a transverse rock-shaft to which the key-levers are loosely applied, two dogs fixed on said rock-shaft and extending one below one of said capital key-levers and the figure-lever, and the other under the other capital key-lever, each dog comprising a circular collar and a radially projecting lug extending exposed in the path of the key-lever radially beyond the hub of the latter, independent lifting-springs one under each of the capital key-levers, a rearwardly-extending arm fixed on said rock-shaft and engaging the lower end of the anvil-shaft of the machine, means for limiting downward movement of one of said capital key-levers, and means for limiting downward movement of the figure key-lever.

6. A shift-key attachment for typewriting machines, comprising a capital shift-

key and a figure shift-key at one side of the keyboard, and an auxiliary capital shift-key at the other side of the keyboard, key-levers for said shift-keys having circular hubs, a transverse rock-shaft to which the key-levers are loosely applied, two dogs fixed on said rock-shaft and extending one below one of said capital key-levers and the figure-lever, and the other under the other capital key-lever, each dog comprising a circular collar and a radially projecting lug extending exposed in the path of the key-lever radially beyond the hub of the latter, independent lifting-springs one under each of the capital key-levers, a rearwardly-extending arm fixed on said rock-shaft and engaging the lower end of the anvil-shaft of the machine, means for limiting downward movement of one of said capital key-levers, and adjustable means for limiting downward movement of the figure key-lever.

7. A shift-key attachment for typewriting machines, comprising a capital shift-key and a figure shift-key at one side of the key-board, and an auxiliary capital shift-key at the other side of the keyboard, key-levers for said shift-keys having circular hubs, a transverse rock-shaft to which the key-levers are loosely applied, two dogs fixed on said rock-shaft and extending one below one of said capital key-levers and the figure-lever, and the other under the other capital key-lever, each dog comprising a circular collar and a radially projecting lug extending exposed in the path of the key-lever radially beyond the hub of the latter, independent lifting-springs one under each

of the capital key-levers, a rearwardly-extending arm fixed on said rock-shaft and engaging the lower end of the anvil-shaft of the machine, and means for locking one of said capital shift-keys in anvil-raised position.

8. A shift-key attachment for typewriting machines, comprising a capital shift-key and a figure shift-key at one side of the key-board, and an auxiliary capital shift-key at the other side of the keyboard, key-levers for said shift-keys having circular hubs, a transverse rock-shaft to which the key-levers are loosely applied, two dogs fixed on said rock-shaft and extending one below one of said capital key-levers and the figure-lever, and the other under the other capital key-lever, each dog comprising a circular collar and a radially projecting lug extending exposed in the path of the key-lever radially beyond the hub of the latter, independent lifting-springs one under each of the capital key-levers, a rearwardly-extending arm fixed on said rock-shaft and engaging the lower end of the anvil-shaft of the machine, means for locking one of said capital shift-keys in anvil-raised position, and means independent of said last-named means for locking the figure key-lever in anvil-raised position.

In testimony, that I claim the foregoing as my invention, I have signed my name in presence of two subscribing witnesses.

ARTHUR LOPEZ.
